ADJUSTABLE LENGTH FOLDING LEGS FOR IRONING BOARDS

John Merner, Milwaukee, Wis., assignor to Geuder, Paeschke & Frey Co., Milwaukee, Wis., a corporation of Wisconsin

Application September 7, 1946, Serial No. 695,351

1-Claim. (Cl. 38—117)

1

This invention relates to improvements in adjustable length folding legs for ironing boards. It is a desirable feature of ironing boards to be able to vary the height of the ironing surface from the floor in order to provide a comfortable position for the user. The different relative angularity of the interconnected folding legs makes the proper selection and adjustment of their adjustable lengths difficult to accomplish and still keep the top level.

An object of this invention, therefore, is to provide adjustable length folding legs for an ironing board in which selective adjustments of one leg may be matched with respective adjustments of other legs to maintain the ironing top level.

A further object of this invention is to provide adjustable length folding legs in which various selective positions may be quickly and readily selected and rigidly maintained.

A still further object of this invention is to provide adjustable length folding legs which are structurally strong, easily operable, and economically manufactured.

These objects are obtained by providing the folding legs of the ironing board with telescopically interfitting foot sections. There is provided on either the leg or the foot section indicating marks to visibly show the predetermined position selected. Such marks are spaced to provide for differences arising from the different relative angular positions of the legs. When correspondingly numbered marks are selected for each leg the top of the ironing board will be level. A clamp is provided to hold the foot section and leg in the selected position. In addition to the clamp there may be provided a plurality of spaced protuberances which in the predetermined selectable relative positions bear against the clamp to keep the foot section from moving upwardly with respect to the leg. With the clamp loose, these protuberances offer slight resistance to the upward movement of the foot section and thus warn the operator when one of the predetermined selectable positions has been reached. At such time the respective indicator mark will also gauge such selected position.

The novel features, which are considered characteristic of the invention, are set forth with particularity in the appended claim. The invention itself, however, both as to its organization and its method of operation, together with additional objects and advantages thereof, will best be understood from the following description of a spe-

2

cific embodiment when read in connection with the accompanying drawing, in which:

Fig. 1 is a view in side elevation of an ironing board provided with adjustable length folding legs embodying the present invention;

Fig. 2 is an enlarged fragmentary front view of the lower part of one of the legs and the extensible foot section;

Fig. 3 is an enlarged sectional view taken on the line 3—3 of Fig. 2;

Fig. 4 is an enlarged fragmentary rear view of the fragmentary view of Fig. 2;

Fig. 5 is a sectional view taken on line 5—5 of Fig. 3; and

Fig. 6 is a sectional view taken on line 6—6 of Fig. 3.

Referring to the drawing by reference numerals, the ironing board 10 is supported on three folding legs 11 interconnected by rods 12 and 13.

Two of the legs 11 are pivoted to the head of the ironing board 11 (right hand viewed in Fig. 1) and a single leg 11 is pivoted to the central portion of the board. When unfolded (as shown in Fig. 1), the front leg 11 has a different angular slope relative to the board than have the two rear legs 11. Thus there is provided a wide tripod-like support for the board. A latch 14, well known in the art, locks the legs in the unfolded position shown in Fig. 1 and unlatches to permit them to be completely folded (not shown).

Each of the legs 11 has identically shaped lower portions of semi-circular cross section, as is clearly shown in Figs. 5 and 6. This structural form has rigidity and is light in weight. Each of the lower portions at their bottoms is provided with a retaining cross member 15. The cross member 15 extends from edge to edge and is secured in place by welding or by other suitable means. It aids in telescopically slideably holding the foot sections. The feet 16 also have a portion of semi-circular cross section which adapts them to slidably telescope within the lower portions of the legs 11. They are slid into such position under the bar 15 which keeps them from falling too far away from the legs during adjustments.

The foot section 16 is provided with an elongated slot 17, the length of which determines the extremes of relative adjustment. This slot 17 slidably accommodates the shank of a bolt 18 which is held in the lower portion of the leg 11 and projects through the slot 17 into the area within the cross sectional confines of the foot section 16. A washer 19, which has a curved sur-

face fitting snugly against the inner curved surface of the foot section 16, is carried on the shank of the bolt 18. A winged nut 20 is threaded to the shank of the bolt 18 and presses against the washer 19 to clamp such washer against the foot section 16 and the latter against lower portion of leg 11, thus holding the section 16 in the selected position. The foot sections may be provided with rubber feet 21, as is well known in this art.

Because the forward leg 11 has a different angular slope relative to the board than the rear legs, it requires a greater distance between selected adjustable positions to effectuate the same ultimate adjustment in height as that accomplished by the rearward legs with a shorter distance between selectable adjustable positions. Therefore, in order to permit the user to make adjustments which automatically keep the ironing board level, the respective foot sections are provided with indicating marks 22 etched or otherwise formed in the outer surface of the foot section 16. These marks are appropriately spaced depending upon the leg to which the foot section is to be interfitted. When one of the indicating marks 22 is in substantial alinement with the bottom edge of leg 11, a predetermined selected position is gauged. In the particular embodiment described herein, there are four such predetermined selectable positions, and in the view of Fig. 2 the foot section 16 is in the third position. If each of the other foot sections are also placed in the same third position by so gauging the indicating marks, the ironing board will be kept level. Thus, the user may readily make adjustments in the height of the ironing board surface and by the use of these visual gauges be assured that the ironing board will be kept in its level position at the newly selected height.

In order to assist the clamp 18, 19, and 20 to hold the foot section 16 in the selected position, there is provided in the marginal edges of the slot 17 a plurality of spaced protuberances 23. These protuberances are raised above the surface of the foot section 16, as is clearly shown in Fig. 3, and bear against the lower edge of the washer 19, thus increasing the resistance of the foot section 16 to upward movement relative to the leg 11. When the clamp is loosened by unscrewing the winged nut 20 and the foot section 16 moved relatively to the leg, the protuberances 23 when they ride under the washer 19 offer greater resistance to such movement. This increased resistance will indicate to the user that one of the predetermined selectable positions has been reached. As the spacing between the protuberances 23 and the indicating marks 22 is the same, one of the marks 22 will be alined with the bottom of the leg when a respective protuberance abuts the lower edge of the washer 19. Thus, the user has two ways of gauging when a selectable position has been reached.

While in this construction the foot section has

been preferably shown telescoped within the leg, substantially the same results may be obtained if the position of the parts were reversed, in which case the indicator marks, protuberances, and elongated slot could all be positioned on the leg rather than on the foot section.

Although only one embodiment of the invention is shown and described herein, it will be understood that this application is intended to cover such changes or modifications as come within the spirit of the invention or scope of the following claim.

I claim:

In an ironing board having folding leg members disposed in different angular positions with respect to the board when positioned to support the board in operative position substantially parallel to a horizontal supporting surface, means incorporated in each leg for adjusting the length thereof for varying the height of the board above said surface comprising telescopically interfitted members including a foot section and a leg section, manually operable means for securing said sections in adjusted positions, and complemental gauge means carried by each leg member to aid in adjusting the foot sections with respect to the leg sections respectively, to assure a substantially horizontal position of the board at different heights above said supporting surface, said gauge means including calibrations on one of the sections of each leg member, and registering gauge means on the other of said sections of each leg member, the calibrations on the several leg members being spaced different distances apart to compensate for the different angular positions of the respective legs with respect to the board, and protuberances provided on one of said sections of each leg member correlated with said calibrations and cooperable with said securing means to facilitate positioning the several foot sections in respect to their respective leg sections.
